UNITED STATES PATENT OFFICE.

LEE SHOWERS, OF CHARLEROI, PENNSYLVANIA, ASSIGNOR TO PITTSBURGH PLATE
GLASS COMPANY, A CORPORATION OF PENNSYLVANIA.

PLATE-GLASS-ROLLING APPARATUS.

Application filed January 29, 1927. Serial No. 164,483.

The invention relates to glass rolling apparatus, and particularly to a device for use in connection with an intermittent rolling machine, such as that shown in my Patent 5 No. 1,579,666, issued April 6, 1926. In the operation of an apparatus, such as that specified, the forward edge of each sheet, as it emerges from between the rolls has a tendency to turn down and catch upon the end 10 of the platen which constitutes the first portion of the runway for receiving the sheets, or, if rolls are used next to the casting roll instead of the platen, the end of the sheet will turn downward between the rolls. It 15 has therefore been necessary, as each sheet is cast, to have an operative stationed opposite the platen to hold the advancing edge of the sheet up by the use of a hand bar, so that it does not catch on the edge of the 20 platen and so that it does not subsequently turn downward between the rolls of the runway which follow the platen. This involves a large amount of labor and is a matter of some difficulty due to the rapid advance of 25 the sheet, ranging from 30 to 50 feet per minute. If the sheet end is not held up in the manner specified, and as a result catches on the edge of the plate, its movement will either be stopped or the end will turn back 30 upon itself so that it cannot be flattened, thus causing a loss of product.

The present invention is designed to overcome the difficulty above set forth, and has for its object the provision of a simple, easily operated device, which will guide and support the end of the sheet until it passes the edge of the platen, and will also chill and stiffen the lower surface of the glass, thus reducing its tendency to turn downward after the supporting device withdrawn. The supporting device is in the form of a plate, adapted to be inserted into the pass between the casting rolls just before the body of molten glass to be rolled is 45 poured into the pocket between the rolls. The plate is suitably supported and moved by operating mechanism, so that it is withdrawn from the pass and acts as a support for the advancing end of the sheet being 50 formed. After such end passes the forward edge of the platen, the plate is withdrawn from beneath such edge. Certain embodiments of the invention are illustrated in the accompanying drawings, wherein:

55 Figure 1 is a vertical section through the

apparatus. Fig. 2 is a section on the line II-II of Fig. 1. Fig. 3 is a plan view of a modified form of apparatus. Fig. 4 is a section through a modified form of apparatus. And Figs. 5, 6 and 7 are detail views 60 showing other modifications.

Referring to the drawings, 1 is an annular casting or rolling member supported upon a pair of driven rolls 2, 2, and 3 is a sizing roll preferably water cooled and supported in a suitable framework 4. This framework is adjustable by means of the pivoted screws 5 for swinging the brackets 6 up and down and so regulating the distance between the roll 3 and the rolling member 1. The body 65 of glass 7 is poured into a pocket between the two rolls, the ends of which are closed by the plates 8. This apparatus is shown only in a diagrammatic way, and requires no further explanation, in view of the disclosure in 70 my patent heretofore referred to, it being understood that the rolls 2, 2 are driven and so drive the rolling member 1, and that the sizing roll 3 is driven in any suitable manner.

The sheet of glass 9 formed between the rolls first passes over the water cooled platen 10 and then over the rolls 11, the platen and rolls together constituting a runway which leads into the leer 12. This leer is of the 75 roller type arranged to permit a gradual cooling of the glass sheets as they pass therethrough until they are thoroughly annealed, such sheets being cut into sections as they emerge at the far end of the leer. A transverse shaft 13 extends across from one bracket 6 to the other bracket and carries a worm for operating the worm wheels 14 which are swiveled to the brackets 6 and serve to adjust such brackets vertically. 80 This shaft 13 acts as a support for a pair of brackets 15, which in turn carry a transverse shaft 16. This shaft has keyed thereto a pair of arms 17 to which are pivoted the 85 hangers 18. The hangers are riveted at their lower ends to a plate 19 which has another plate 20 hinged to its lower edge. The full lines in Fig. 1 indicates these parts in one position, while the dotted lines indicate the parts in another position. The end of the 90 shaft 16 is provided with a handle 21 having an extension 22 carrying the counterweight 23. This counterweight normally tends to hold the parts in the position 95 shown in full lines.

Supported upon a transverse tube 24 and the angle 25 are a pair of guide or cam strips 26 having their ends curved downwardly, as shown in Fig. 1 and adapted to engage the end of the plate 20.

When a sheet of glass is about to be cast, but before the body 7 is supplied between the rolls, the handle 21 is swung to the left, causing the plate 20 to move to the position indicated in dotted lines. It is guided in this movement, first, by the curved end of the cam strips 26 and then by the surface of the platen 10 and the surface of the roll 1. When the body of glass 7 is poured into the pocket between the rolls, the lower portion of such glass flows over the inner end of the plate 20 and, as the sheet is rolled out between the rolls, the operator swings the handle 21 to the right so that the end of the sheet 20 continues beneath the end of the glass sheet until such end is guided onto the platen 10. As the glass sheet moves forward still further, the handle 21 is operated more rapidly so that the plate 20 is withdrawn from beneath the glass and reaches the position shown in full lines, at which point it will be maintained by the counter-weight 23. The plate 20 not only serves the function of guiding the end of the glass sheet over the joint between the roll 1 and the right hand end of the platen 10, but also serves to chill the lower surface of the glass, so that after the glass passes on to the rolls 11, it has no tendency to turn downward between the rolls.

When very wide sheets of glass are to be rolled, it may be desirable to make the plate 20 in several sections, as indicated in Fig. 3, the plate here being made up of the three sections 27, 27, 27 which are mounted upon the shaft 16 by means of the arms 28, the hangers 29 and the plates 30.

Fig. 4 illustrates a modification in which a different means is employed for withdrawing the guiding plate 31 from the rolls 1 and 3. In this construction, the left hand end of the plate is hinged to a chain 32 mounted for movement around sprockets on the shafts 33 and 34, the shaft 34 being rotated by means of the hand wheel 35. As the sheet is formed, the hand wheel 35, is rotated and the plate 31 moved to the left, its lower end following the surface of the roll 1 and that of the platen 36 until the glass is upon the platen, after which the hand wheel 35 is rotated still faster to withdraw the plate along the line of movement of the upper flight of the chain 32 and out of the way of the advancing end of the glass sheet. Various other means might be employed for giving the plate 31 its movements, and if desired, this might be made automatic by providing mechanical operating means between the shaft which operates the plate and actu-

ating means moving in timed relation with the rolls 1 and 3.

Figs. 5, 6 and 7 illustrate modifications of the guide plates. The plates 37 of Fig. 5 being arranged so that their lower edges are concave, the edges of the plates 38 in Fig. 6 being convex and the edges of the plates 39 in Fig. 7 being inclined or tapered.

What I claim is:

1. The combination with a pair of substantially horizontal glass sheet forming rolls and a runway in advance thereof and extending laterally, of means for guiding the advancing end of the glass sheet formed between the rolls onto the runway comprising, a plate in advance of the rolls, a support therefor to which the plate is hinged, and means for moving the plate up into the pass between the rolls with its lower side in contact with the lower roll, and for withdrawing the plate from said pass with the front end of the glass sheet which is formed supported on the plate.

2. The combination with a pair of substantially horizontal glass sheet forming rolls and a runway in advance thereof and extending laterally, of means for guiding the advancing end of the glass sheet formed between the rolls onto the runway comprising, a plate also in advance of the rolls, adapted to be moved into the pass between the rolls and receive the end of the glass sheet formed therebetween, and operating means for moving the plate into said pass and for withdrawing it from beneath the end of said sheet after such end has been guided onto the runway, said plate being hinged at one edge to said operating means, and having its other edge positioned so that it rests upon and is guided by the runway and the lower roll during its movement into the pass between the rolls.

3. The combination with a pair of substantially horizontal glass sheet forming rolls and a runway in advance thereof and extending laterally, of means for guiding the advancing end of the glass sheet formed between the rolls onto the runway comprising, a plate also in advance of the rolls, adapted to be moved into the pass between the rolls, and receive the end of the glass sheet formed therebetween, and operating means for moving the plate into said pass and for withdrawing it from beneath the end of said sheet after such end has been guided onto the runway, said operating means being counterbalanced, so that it normally holds said plate in withdrawn position spaced above the runway.

In testimony whereof, I have hereunto subscribed my name this 3rd day of January 1927.

LEE SHOWERS.
